CONTROL FOR VAPOR DISCHARGE TUBES
AND ELECTRIC ARCSEugene H. Haug, Glenoce, Ill., assignor, by direct
and mesne assignments, to Modern Controls,
Inc., Chicago, Ill., a corporation of Delaware

Application April 3, 1944, Serial No. 529,253

5 Claims. (Cl. 323—7)

1

My invention relates to an electric control circuit for vapor discharge tubes and electric arcs, and more particularly to such loads having a negative resistance characteristic and requiring a distorted voltage or current wave in their operation.

Heretofore there have been proposed several arrangements of control circuits, such as the high leakage transformer or series reactors. All these controls have the defect of taking from the supply circuit either a distorted current wave or voltage wave, thereby creating a low power factor in the supply circuit, and causing radio and telephone interference. In certain arrangements of the prior art attempt has been made to overcome such defect by the use of shunt capacitors across the supply circuit. If capacity reactance be paralleled in the primary supply circuit in an effort to improve the power factor, the optimum power factor will only be obtained when the fundamental component of the current wave is in phase with the impressed sinusoidal voltage wave. Under these conditions the harmonic components of the current wave will remain unaltered, since with a sinusoidal impressed voltage capacitance they can draw only current possessing a sinusoidal wave. In other words, shunt capacitance cannot, under any condition, correct power factor due to a distorted current and voltage wave.

It is an object of my invention, therefore, to provide an improved alternating current control system for improving the power factor due to current and voltage wave form distortion.

It is another object of my invention to provide an alternating current control system which will not distort the current or voltage wave in the supply circuit, although the load requires a distorted voltage wave, thereby eliminating radio and telephone interference.

It is another object of my invention to provide an improved alternating current control system which has the advantage of higher apparatus economy.

It is another object of my invention to provide an improved alternating current control system which is conducive to long tube and lamp life.

It is another object of my invention to provide an improved alternating current control system which eliminates the use of high voltages on those parts of the apparatus which are accessible to the operator, thereby providing a personal safety factor.

These and other objects that will be made apparent throughout the further description of my invention are obtained by use of the control sys-

2

tem hereinafter described and illustrated in the accompanying drawings, wherein—

Figure No. 1 is a wiring diagram of my control system for use in operating cold cathode vapor discharge tubes and high voltage arcs.

Figure No. 2 is an oscillograph showing the distorted current wave in the supply circuit and the phase relation of this distorted current wave in relation to the supply voltage when using present day equipment.

Figure No. 3 is an oscillograph showing the non-distorted current wave in the supply circuit and the phase relation of this non-distorted current wave with reference to the supply voltage wave when operating the load on my new improved control system.

Figure No. 4 is a wiring diagram of my control system for use in operating hot cathode vapor discharge tubes and low voltage arcs.

Figure No. 5 is a wiring diagram of my control system similar to that shown in Figure No. 4 except that the air gap is in the center common core instead of the cores of each window, and the reactance value of each coil is controlled by tap arrangements.

Referring to Figure No. 1, 1 and 2 are the alternating current supply lines. Line 1 is connected to coil 4 of the special double reactor 12. Coil 4 has its other end connected to line 5, which is in turn connected to line 9. A capacitor 8 is connected between lines 9 and 2 by means of lines 6 and 7. Coil 21 is connected in series circuit relation with coil 4 by means of lines 5, 9 and 10. Coil 21 is mounted on the core of special double reactor 12. Transformer 16 has one end of its primary 14 connected to coil 21 by means of line 11, and the other end of primary 14 is connected to line 2. The secondary 15 of transformer 16 is connected to load 19 by means of lines 17 and 18.

The operation of Figure No. 1 is as follows: the alternating current supply, which is of constant potential characteristic, is fed to reactor 12 and capacitor 7 in a manner that constant current is produced in the primary 14 of transformer 16. The production of this constant current is controlled by the air gaps 3 and 13 of special reactor 12 in such a manner that the voltage across capacitor 8 tends to regulate the current to the primary of transformer 16. It will be further noted that in this arrangement the two coils of special double reactor 12 are in series circuit relation with one end of primary 14 of transformer 16. The capacitor 8 is mid-tapped between coils 21 and 4 in a manner to act as a T connection wave trap. This form of

T connected wave trap, with the proper relation of the air gaps 3 and 13, has the electrical characteristics of producing sinusoidal waves of currents and voltages when fed from a distorted current or voltage wave. Furthermore, since special double reactor 12 in conjunction with capacitor 8 acts as a resonant form of constant potential to constant current device, the voltage across load 18 will always be of such a value that it will readily restrike the arc at a very early period of each alternation of the alternating current supply. 10

Figure No. 2 shows the wave form of the current as indicated at 1 and the voltage as indicated at 2. When high reactance and high leakage transformers are connected to lines having non-sinusoidal voltage waves, a current wave of non-sinusoidal form will flow. 15

Figure No. 3 shows the wave form of the current as indicated at 1 and the voltage as indicated at 2, when my control is used. It will be noted that the current wave 1 of Figure No. 2 lags the voltage wave by about 72 degrees (31% power factor) and contains both the 3rd and 5th harmonics of appreciable magnitude, while in Figure No. 3 the current wave 1 is sinusoidal in characteristic and that this sinusoidal current wave 1 is in phase with the sinusoidal voltage wave 2. 20

Referring to Figure No. 4 the alternating current supply lines 1 and 2, the special double reactor 12, and the capacitor 8, are similarly connected as in Figure No. 1, the difference between Figure No. 1 and Figure No. 4 being that while Figure No. 1 has a step up transformer 16 and a cold cathode tube 19, Figure No. 4 has no step up transformer to the load, which is a hot cathode tube having two heater type electrodes 22 and 23 at opposite ends, with a starting device 18 connected to heater type electrode 22 by line 17, and to heater electrode 22 by line 19. Since load 26 is a hot cathode tube with heater electrodes 22 and 23, the voltage consumed is very much lower than the voltage consumed by the cold cathode tube 19 of Figure No. 1, and therefore the hot cathode tube 26 of Figure No. 4 does not require a step up transformer 16 as indicated in Figure No. 1. 30

While I have described what I at present consider the preferred embodiment of my invention, it will be obvious to those skilled in the art that various changes and modifications may be made without departing from my invention, and I therefore aim in the appended claims to cover all such changes and modifications as fall within the true spirit and scope of my invention. 35

Because on open circuit in any constant current device the voltage will go to infinity, it becomes important to protect the constant current network and the load circuit against such high potential. Therefore the transformer 16 must be especially constructed so that on full load, the operator is, instead of being on the straight portion of the saturation flux current as is usual, on the knee of the curve. There are many ways in which such a transformer may be constructed, special grades of core material may be used or the core may be restricted but in any event some such special arrangement must be provided with a circuit such as the one I disclose whereby the open circuit voltage of the constant current network will be held down to a safe and reasonable limiting value and any structure that will insure this by limiting the saturation of the core will accomplish this purpose. 40

The use of the double reactor with an air gap of different value in each core is highly important

because with respect to the coil on the intake side of the circuit, namely the coil 4, you get any relationship to the coil on the transformer side of the circuit, namely the coil 21, the following result that coil 4 will produce a constant current in conjunction with the capacitor and coil 21 in conjunction with the capacitor produces a wave trap so that the supply line will not be adversely affected by harmonics produced in the load. 5

What I claim as new and desire to secure by Letters Patent of the United States is:

1. In combination with a constant potential to constant current control device, a constant potential alternating current supply, a double reactor having two windows, a capacitor, a current transformer, and a load circuit, said double reactor having two coils mounted one each on the core of each window, and said double reactor having an air gap in the core of each of said windows, said capacitor being connected between the two coils of said double reactor and one side of said constant potential alternating current supply, the two air gaps being of different value, said current transformer having its primary connected to the output circuit of said constant potential to constant current transformation device and its secondary connected to said load circuit, said reactor having a tap arrangement so that the constant current in the load circuit may be set to any desired value, and said current transformer having its core so constructed that upon an open circuit in said load circuit the magnetic flux density is so limited that the voltage across the secondary of said current transformer is held to a safe value. 20

2. In combination with a constant potential to constant current control device, a constant potential alternating current supply, a double reactor having two windows, a capacitor, and a load, said double reactor having two coils mounted one each on the core of each window, and said double reactor having an air gap in the core of each of said windows, said capacitor being connected between the two coils of said double reactor and one side of said constant potential alternating current supply, the two air gaps being of different value. 30

3. In combination with a constant potential to constant current control device, a constant potential alternating current supply, a double reactor having two windows, a capacitor, and a load, said double reactor having two coils mounted one each on the core of each window, and said double reactor having an air gap in the center core, said capacitor being connected between the two coils of said double reactor and one side of said constant potential alternating current supply. 40

4. In combination with a constant potential to constant current control device, a constant potential alternating current supply, a double reactor having two windows, a capacitor, a current transformer, and a load circuit, said double reactor having two coils mounted one each on the core of each window, said capacitor being connected between the two coils of said double reactor and one side of said constant potential alternating current supply, each coil of the double reactor having a different reactance value, one coil serving with the capacitance as a wave trap, the other serving with the capacitance to provide constant current for the transformer. 50

5. In combination with a constant potential to constant current control device, a constant potential alternating current supply, a double reactor having two windows, a capacitor, and a load circuit, said double reactor having two coils mounted

one each on the core of each window, said capacitor being connected between the two coils of said double reactor and one side of said constant potential alternating current supply, each coil of the double reactor having a different reactance value, one coil serving with the capacitance as a wave trap, the other serving with the capacitance to provide constant current for the transformer.
